FLOOR WAXER

Don L. Rubinfield, Lorain, Ohio, assignor, by mesne assignments, to Master Mfg. Co., Inc., Cleveland, Ohio, a corporation of Ohio

Filed Oct. 29, 1954, Ser. No. 32,875

Term of patent 14 years

(Cl. D9—2)

The handle is shown broken away in FIGURES 4 and 8 for convenience of illustration.

I claim:

The ornamental design for a floor waxer, substantially as shown and described.
